CLAIM

The ornamental design for a folding pamphlet blank, as shown and described.

DESCRIPTION

FIG. 1 is a plan view showing my new design for a folding pamphlet blank,

FIG. 2 is a left side end view thereof;

FIG. 3 is a front elevational view thereof;

FIG. 4 is a right side end view thereof;

FIG. 5 is a rear elevational view thereof;

FIG. 6 is a bottom view thereof; and,

FIG. 7 is a perspective view of the unfolded blank used in forming the folded pamphlet blank of the present invention.
